WINDOW FRAME AND WALL JOINT
CONSTRUCTIONSern Madsen, Clinton, Iowa, assignor to Curtis
Companies Incorporated, Clinton, Iowa, a cor-
poration of Iowa

Application October 19, 1931. Serial No. 569,633

2 Claims. (Cl. 20—11)

An object of my invention is to provide a window frame and wall joint construction which is simple, effective, durable and comparatively inexpensive to manufacture.

More particularly, it is my object to provide simplified means for making a joint between a window frame and a wall construction which is entirely leak-proof. This is often attempted by the use of a wide blind stop or a blind stop extension which involves cutting off the wall sheathing boards at the center of the studding, which is objected to by builders. Such a joint is not necessarily tight because an extra blind stop nailed to a studding is not always tight due to warp or unevenness in the studding. If the blind stop is formed of two pieces there is a possibility of air leaking through the joint between the two pieces due to shrinkage of the wood parts. The use of a wood blind stop extension also causes or requires several kinds of different frame constructions in order that the frame may space up correctly in the wall. Where wood blind stop extension is used in a brick wall, it requires chipping the corners of one row of bricks to build around the stop. Shrinkage of the blind stops causes an open joint.

It is, therefore, one of the main objects of my invention to provide means for connecting and sealing the space between a frame of any type and a wall construction in which the frame is set, such means consisting of a strip of material having its opposite edges set in a window frame and in a wall construction in such manner that all possibilities of an open joint because of shrinkage or for other reasons is entirely eliminated.

A further object is to provide a groove preferably formed by rabbeting the blind stop so that the rabbeted portion in conjunction with the outer casing forms the groove into which one edge of the strip of material may be snugly inserted.

A further object is to provide such groove of relatively deep and narrow character so as to minimize enlarging of it because of shrinkage of parts.

Still a further object is to provide the strip of material of flexible or bendable character whereby to take up all unevenness and whereby it can be bent to offset position as may be required when constructing certain forms of walls around the frame.

Another object is to provide the strip of material of such relative thinness that it is adaptable to occupy permissible space between ad-

joining layers of a wall, such as occupying a position between sheathing and an outer wall covering or between courses of brick or masonry, without departing from the usual construction of the wall.

With these and other objects in view my invention consists in the construction, arrangement and combination of the various parts of my device, whereby the objects contemplated are attained, as hereinafter more fully set forth, pointed out in my claims, and illustrated in the accompanying drawing, in which:—

Figure 1 is an outside elevation of a window frame embodying my invention.

Figure 2 is an enlarged sectional view on the line 2—2 of Figure 1, showing a sheathed wall construction with my invention applied thereto.

Figure 3 is a separated perspective view of the parts shown in Figure 2.

Figure 4 is an enlarged sectional view on the line 4—4 of Figure 1, showing the construction at the head of the window.

Figure 5 is a sectional view similar to Figure 2, showing my invention used in connection with a brick or masonry wall.

Figure 6 is a sectional view similar to Figure 2 showing another type of installation to illustrate the purpose for providing a strip of material which is bendable.

Figure 7 is another sectional view similar to Figure 2 showing the invention applied to a frame other than a window frame; and

Figure 8 is a view similar to Figure 6 showing another way of securing the strip of material to the frame.

On the accompanying drawing I have used the reference character A to indicate generally a window frame and B, a wall construction.

In general, the window frame A has side jambs 10, a head jamb 12, side blind stops 14, a head blind stop 16 and side and head outer casings 18 and 20, respectively. In Figure 2, I have shown the wall construction B as being of the sheathed type in which the studding is indicated at 22 and the sheathing at 24. Building paper is usually used on the outside of the sheathing 24 as indicated at 26. The outer surface of the wall may be of any construction, such as stucco, brick veneer or siding 28 as illustrated in Figures 2 and 3.

In order to seal the space between the sheathing 24 and the side blind stop 14, I form a rabbet 30 in the outer face of the blind stop whereby to provide a groove between the rabbeted portion and the inner face of the side casing 18. A strip of material 32 extends into the groove formed by 110

the rabbet 30 and fits snugly therein so as to prevent infiltration of air and weather between the casing 18, the strip 32 and the blind stop 14. The outer edge of the strip 32 is adapted to be imbedded in the wall construction B, preferably lapping over the building paper 26 where such is used.

In Figure 3, I have shown the parts separated with arrows *a* indicating the movements of the parts to assume assembled position. This is just in order to illustrate how the parts coact with each other.

The strip of material 32 may be formed of building paper, metal or any desired composition, it being preferably thin and flexible or bendable. It is flexible so that it can conform to any irregularities in the sheathing 24 or in any surface with which it coacts in the wall construction so as to avoid any possibility of air or weather passing between the strip and the portion of the wall construction with which it engages.

In Figure 5, I have shown a wall construction B composed of bricks 34 and the strip of material 32 is fitted between the courses of the brick. The strip 32 of course can be used with any type of masonry wall with the same effectiveness. In Figure 4, I have shown the head blind stop 16 as having a rabbet 30a for a strip 32a to extend into. The strip 32a, it will be noted, laps over the building paper 26a in the same manner as shown in Figure 2. When building the wall around the frame if the frame must be set farther out or in, the strip 32 can be bent as desired to accommodate such adjustment.

The strip of material 32 preferably extends down past the sill 11 as shown in Figure 1. The sill is provided with a notch 13 to accommodate such extension. The notch 13 is shown dotted in Figures 2 and 5. After the two side strips 32 are placed in position relative to the window frame A the head strip 32a may be considered to extend between and lap over them. Only one of the strips 32 is shown in Figure 1, the other one being omitted and the bottom of the rabbet 30 and groove 13 being indicated by dotted lines.

Providing a relatively deep and narrow rabbet 30 and a relatively thin strip of material 32 reduces shrinkage to a minimum because of the slight width of the slot or groove formed by the rabbet 30. By the term "relatively thin" the intention of my meaning is that the sheet of material 32 is of a thickness adaptable to occupy permissible space between sheathing and outer wall covering without changing the usual wall construction, and such thickness of course must be considerably thinner than sheathing which is the usual thickness of an extension blind stop. It is quite desirable that the sheet of material 32 should be thin enough so that it is insertable in the space permissible between adjoining layers of brick or masonry walls without departing from the usual construction of such walls.

The joint is economical and efficient and yet is very simple and easy to install in any type of wall construction. The groove formed by the rabbet 30 is positioned at a point not subject to bad effects of shrink and swell of the parts.

Although I have shown the groove formed by the rabbet 30 as being between the blind stop and outer casing of a window frame, it may be located at any other desirable point or between other elements of the window frame, such as between the side jamb and the blind stop for instance.

In Figure 6, I have shown why it is desirable

to have the strip 32 of flexible or bendable material. In the wall construction B shown in Figure 6 sheathing is indicated at 36 with a furring strip 38 secured thereto for mounting wood or metal lath or the like 40 against which either a stucco or brick veneer outer wall covering 42 is applied. In this type of construction it will be noted that the sheathing 36 is considerably offset from the blind stop 14 instead of in alignment therewith as shown in Figure 2. The strip 32 extends over the member 38 and may be secured to the sheathing 36 by a lath strip 44 or the like. The lath 40 laps over the strip 32 and it will be evident that since the strip is flexible it may be bent to contact with and be secured to any offset portion of the wall construction. The strip 32 will thus also lap and form a tight joint with the building paper 26 usually applied on the sheathing 36.

The use of the strip 32 need not be restricted to window frames only but may be used for door and other frames. The groove to receive the strip need not be in exact position shown but may for instance be formed in the outer casing. I have illustrated this construction in Figure 7 in which a door jamb 46 is shown having an outer casing 48. A groove 50 is formed in the side of the casing 48 next to the wall construction B and the edge of the strip 32 extends into the groove 50. Although this is a departure in arrangement from the arrangement of Figure 2, the strip 32 nevertheless forms an effective air and weather seal between the wall construction B and the frame parts 46 and 48.

The joint between the strip 32, the blind stop 14 and the casing 18 when once tightened will normally remain tight and when the outer edge of the strip is imbedded in mortar if there is any shrinkage at all in the thickness of the strip it will be very slight because it would be in proportion to the thickness of the strip and the strip is relatively thin.

Another advantage in using a thin strip for closing the joint is that it occupies but very little space and does not require special, more expensive wall construction for its use. It is adaptable because of its thin construction to work into spaces left between ordinary materials of construction, such as between the building paper 26 and the siding 28, as shown in Figure 2.

In practicing the invention, the rabbets 30 and 30a may be cut in the window frame at the factory and the strip 32 is always available on the job in the form of building paper where the frame is being installed. Strips of metal, roofing felt or tear resisting sheet material may also be used as desired.

The groove to receive the strip of material 32 need not be confined in location to the space between the casing and blind stop as illustrated.

In Figure 8, I have shown a construction in which the strip 32 may be overlapped with the jamb 18 or any part of the frame and a tight joint may be made therewith by means of a strip 51 and nails or the like 52. I have shown the strip 32 as contacting along two sides of the strip 51, but it is obvious that it can contact with only one side thereof and the strip 51 need not necessarily be quarter round as illustrated. The main requisite is that an attaching strip should be provided between which and the window frame the strip 32 may be tightly secured in a weatherproof manner. It is, therefore, obvious that a groove does not need necessarily to be provided for the strip 32, but other means as I have illustrated can

be used to fasten the strip 32 to the frame for the desired purpose of providing an effective joint between the frame and the wall construction.

Other changes may be made in the construction 5 and arrangement of the parts of my device without departing from the real spirit and purpose of my invention and it is my intention to cover by my claims, any modified forms of structure or use of mechanical equivalents, which may be 10 reasonably included within their scope.

I claim as my invention:

1. In a window frame and wall joint construction, a window frame having a sill, head and side jambs, head and side blind stops and head 15 and side casings, said blind stops extending slightly outward from the outer face of said jambs and being rabbeted adjacent said casings, the ends of said sill extending beyond said side jambs and each end having a vertical slot cut 20 therethrough in alignment with the rabbets of said side blind stops, flat strips of thin, bendable material cut from regular stock material received in the grooves formed by said rabbets between said blind stops and said casings, the upper 25 ends of the strips along the side casings overlapping the ends of the strip along the head casing to provide a continuous joint around three sides of said window frame, the outer edges of

said strips being interposed between layers of an adjacent wall construction and the lower ends of the strips along the side casing extending through the slots of said sill and past the lower surface of said sill.

2. In a window frame and wall joint construction, a window frame having a sill, head and side jambs, head and side blind stops and head and side casings, said blind stops and casings having outwardly opening grooves formed between them, the ends of said sill extending beyond said side jambs and each end having a vertical slot cut therethrough in alignment with the grooves between said side casings and said side blind stops, flat strips of thin, bendable material cut from regular stock material received in the grooves formed between said casings and said blind stops, the upper ends of the strips along the side casing overlapping the ends of the strip along the head casing to provide a continuous joint around three sides of said window frame, the outer edges of said strips being interposed between layers of an adjacent wall construction and the lower ends of the strips along the side casings extending through the slots of said sill and past the lower surface of said sill.
